CLAIM

The ornamental design for display stand, as shown and described.

DESCRIPTION

FIG. 1 is a perspective view of the display stand; FIG. 2 is a top plan view thereof; FIG. 3 is a front elevational view thereof, the rear view being essentially a mirror image thereof; FIG. 4 is a side elevational view thereof, the other side being essentially a mirror image thereof; and, FIG. 5 is a perspective view of the display stand, the only difference between this view and FIG. 1 being the absence of a display tower in the central frame.

The broken line illustration of five display towers and hinges in FIGS. 1 through 5 is for illustrative purposes only and forms no part of the claimed design.
